WHEELED PUSH TOY

Henry J. Kelly, Buffalo, N.Y.

Application March 19, 1958, Serial No. 722,488

7 Claims. (Cl. 46—114)

The present invention generally relates to a toy and more particularly a push type toy in which there is provided a simulated globe mounted on a wheel together with a handle for pushing the device along a supporting surface and together with a satellite mounted for movement in relation to the globe and together with a sound producing mechanism operated by the satellite for providing a beeping sound as the toy is pushed along a supporting surface.

The primary object of the present invention is to provide a toy which simulates the action of a satellite circling the earth, the top being in the form of a push type toy and there also being provided sound producing mechanism for providing a beeping sound for the device.

Another object of the present invention is to provide a toy which is extremely simple in construction, easy to use, intriguing in its operation and relatively inexpensive to manufacture.

These together with other objects and advantages which will become subsequently apparent reside in the details of construction and operation as more fully hereinafter described and claimed, reference being had to the accompanying drawings forming a part hereof, wherein like numerals refer to like parts throughout, and in which:

Figure 1 is a perspective view of the toy of the present invention;

Figure 2 is a detailed sectional view taken substantially upon a plane passing along section line 2—2 of Figure 1 illustrating the details of construction thereof; and

Figure 3 is a detailed sectional view taken substantially upon a plane passing along section line 3—3 of Figure 1 illustrating the manner in which the handle is attached to the globe in straddling relation to the wheel.

Referring now specifically to the drawings, the numeral 10 generally designates the toy of the present invention which includes a globe generally designated by the numeral 12 which is divided into two hollow hemispheres 14 and 16 each of which may be provided with coloring or similar indicia on the external surface thereof for indicating or simulating the earth with the land and water bodies thereon. Each hemisphere 14 and 16 is provided with an inwardly extending cylindrical sleeve 18 at the center thereof for journaling the hemispheres 14 and 16 on a transverse axle 20. Centrally disposed on the axle 20 is a wheel hub 22 secured thereto as by a transverse pin 24. Extending radially from the hub 22 is a plurality of spokes 26 which are interconnected by an annular wheel rim 28. The spokes 26 extend outwardly through a space between the two hemispheres 14 and 16 and are longer than the radius of the globe 12 whereby the wheel rim 28 is disposed in spaced relation to the periphery of the globe 12.

For propelling the toy along a supporting surface, an elongated handle 30 is provided. The inner end of the handle 30 is bifurcated into two legs 32 termi-

2

nating in out turned flanges 34 which are attached to the hemispheres 14 and 16 respectively by fastening bolts 36. Thus by pushing on the handle 30, the wheel 28 may be caused to rotate along with the axle 20 with the globe 12 remaining relatively stationary while the axle 20 turns in the sleeves 18.

Mounted rigid with one end of the axle 20 is an elongated curved wire rod 38 which extends in spaced relation along the surface of the hemisphere 16. Mounted on the free end of the wire rod 38 is a spherical member 40 having projections 42 thereon which simulates a satellite in appearance. Thus when the toy is pushed along a supporting surface, the axle 20 will rotate causing the spherical member 40 to move in a circular path substantially in an orbit about the hemisphere 16 generally in the nature of a satellite.

Mounted in the hemisphere 16 is a sound producing mechanism generally designated by the numeral 44 which is capable of producing a beeping sound and which includes an actuating lever or pin 46 extending through an aperture 48 in the hemisphere 16. The actuating arm or lever 46 is disposed in the path of movement of the spherical satellite 40 whereby the satellite 40 will engage the arm 46 during each revolution about the hemisphere 16 thus causing the sound producing mechanism 44 to be actuated. Thus, the device will provide a "beep, beep, beep" as it is pushed along, the sound producing mechanism 44 being any well known and conventional type capable of producing a beeping sound responsive to pivotal or depressing movement of the actuating arm 46.

With the present invention, a highly novel and entertaining toy device may be provided which actually simulates a satellite encircling the globe, both in appearance and in sound.

The foregoing is considered as illustrative only of the principles of the invention. Further, since numerous modifications and equivalents may be resorted to, it is not desired to limit the invention to the exact construction and operation shown and described and accordingly, all suitable modifications and equivalents may be made without departing from the scope of the invention as claimed.

What is claimed as new is as follows:

1. A push type toy comprising a horizontally disposed axle, a wheel mounted centrally on said axle in rigid relation thereto, a pair of semi-spherical members mounted on said axle with the radius of the semi-spherical members being less than that of the wheel, means retaining the semi-spherical members on the axle with the inner edges thereof in closely spaced relation for permitting movement of the spokes of the wheel, a handle attached to both of said semi-spherical members for pushing the device along a supporting surface whereby the semi-spherical members will be substantially stationary during rotation of the axle and wheel, a curved wire arm secured to one end of said axle and extending along the surface of one of the semi-spherical members, and a simulated satellite on the end of said wire member whereby the simulated satellite will orbit about one of the semi-spherical members.

2. The combination of claim 1 wherein said one of the semi-spherical members is provided with a sound producing device having an actuating arm projecting outwardly from the surface of the semi-spherical member with the arm being disposed in the path of movement of the satellite whereby engagement of the satellite therewith will cause a sound to be produced.

3. The combination of claim 2 wherein said handle means includes an elongated handle having a bifurcated inner end disposed in partially encircling relation to the

periphery of the wheel with the legs thereof mounted rigid with the semi-spherical members thereby constituting the means for retaining the semi-spherical members on the transverse axle.

4. In a wheel toy, the combination of a horizontally disposed rotatable axle, a wheel secured centrally to said axle for rotation therewith, a pair of hemispherical members rotatably mounted on said axle at opposite sides of said wheel whereby the wheel and the axle may rotate when said members are relatively stationary, said members being of a smaller diameter than said wheel whereby the periphery of the wheel is spaced radially outwardly from said members, and a handle having a bifurcated end straddling the peripheral portion of said wheel and rotatably receiving the same therein, the furcations of said handle being secured to said hemispherical members.

5. The toy as defined in claim 4 together with a curved arm rigid with one end of said axle and extending in spaced relation along the surface of one of said hemispherical members toward the peripheral portion of said wheel, and a simulated satellite carried by the free end of said arm for rotation with the axle and wheel.

6. The toy as defined in claim 5 together with a sound producing device mounted in said one of said hemispherical members and including an outwardly projecting actuating element disposed in the path of movement of said simulated satellite.

7. A push type wheel toy comprising in combination, an elongated handle having a bifurcation end providing a pair of spaced furcations, a simulated globe com-

prising a pair of hollow hemispherical members secured to the respective furcations of said handle and having closely spaced adjacent edges, a pair of coaxial bearing sleeves secured in the respective members and having a horizontal axis transverse to the plane of said handle, an axle rotatably journaled in said sleeves, a wheel including a hub secured to an intermediate portion of said axle, spokes radiating from said hub and extending freely outwardly through the space between said adjacent edges of said members, and a rim provided at the outer ends of said spokes in outwardly spaced relation from said members and freely rotatable between the furcations of said handle, a curved arm rigid with one end of said axle and extending in spaced relation along the surface of one of said members, a simulated satellite carried by the free end of said arm at one side of said wheel, said wheel and said axle with said arm and said satellite being rotatable while said globe and said handle are relatively stationary, and a sound producing device mounted in said one of said members and including an outwardly projecting actuating element disposed in the path of movement of said satellite, whereby said sound producing device may be actuated by engagement of the satellite with said element during rotation of said axle and wheel.
